UNITED STATES PATENT OFFICE

CHARLES H. J. DILG, OF NEW YORK, N. Y.

BRUSH-HOLDER FOR DYNAMO-ELECTRIC MACHINES.

1,271,863.

Specification of Letters Patent.

Patented July 9, 1918.

Original application filed January 7, 1913, Serial No. 740,641. Divided and this application filed October 9, 1917. Serial No. 195,498.

To all whom it may concern:

Be it known that I, CHARLES H. J. DILG, a citizen of the United States, residing at the city of New York, in the borough of 5 Manhattan and State of New York, have invented certain new and useful Improvements in Brush-Holders for Dynamo-Electric Machines, of which the following is a full, clear, and exact description.

10 My invention relates to brush holders for dynamo-electric machines, this application being a division of my application Serial Number 740,641, filed January 7, 1913. An object of my invention is to provide a construction of brush holder which will be simple and inexpensive, while effectively holding the brush at all times in good contact with the commutator. Another object is to afford ready access to the brush for the purpose of obtaining or adjusting the resilient pressure of the brush against the commutator, or for other purposes. Another object is to provide a unitary structure which may be easily and conveniently attached to or 20 removed from the machine. Still other objects and advantages of my invention will appear from the following description.

In accordance with my invention I provide a guide tube for the brush which is 30 preferably stamped out of sheet metal so as to leave a longitudinal opening along one side, thereby readily affording access to the brush. One or more supporting arms are provided which are preferably integral with the tube portion and joining the same at one or both edges of the longitudinal opening. A resilient pressure device bears against the rear end of the brush, and the longitudinal opening in the tube is convenient for entering the pressure device from without the tube, or for providing access to adjust the pressure. The resilient pressure device may be conveniently mounted externally of the tube and have a portion 40 extending within the opening and bearing against the brush and another portion extending in front of the longitudinal opening and preventing the brush from escaping from the opening. Preferably the pressure device is so mounted that it has a torque, and a desirable construction is to pivot the device on one of the supporting arms, a spring engaging the device and producing the torque. My invention also comprehends

other features of construction as will hereinafter more fully appear. 55

I shall now describe the illustrated embodiments of my invention and shall thereafter point out my invention in claims.

Figure 1 is a side elevation of a dynamo-electric machine with brush holders embodying my invention; 60

Fig. 2 is a rear end elevation of the same;

Figs. 3 and 4 are details in front and end elevation of the brush holder. 65

The illustrated embodiment of my invention is stamped out of a single piece of sheet material, such as sheet brass, to form a guide tube 1, open along its rear side to provide access to the brush 2, and to form two integral supporting arms 3 and 4 provided with elongated openings for attaching to insulated supports on the rear head of the motor casing, as shown in Figs. 1 and 2, the elongated openings permitting 70 adjustment of the holder to bring the brush into proper position with respect to the commutator 5. To hold the brushes in engagement with the commutator, resilient pressure means are provided arranged to bear 75 against the outer or rear end of each brush, and comprising a pivotal arm 6, pivoted to the lower supporting arm 4 and bifurcated at its upper end. One portion or finger 7 extends upwardly in front of the open side 80 of the guide tube 1 in position to hold the outer end of the brush 2 from escaping from the guide tube, and this finger 7 is turned outwardly at its upper end to provide a convenient handle for manipulating 85 the pivoted pressure member. The other portion of the bifurcated end is bent inwardly and extends into the guide tube 1 in the rear of the brush 2 to provide an engaging finger 8 adapted to bear against the outer end of the brush. To cause the engaging finger 8 to exert yielding pressure 90 against the brush to hold its inner end in engagement with the commutator, a coiled spring 9 is employed, which is attached at one end to a lug or an integral ear 10 on the supporting arm 4, and at its other end to an ear 11 on the pressure arm 6, and resiliently holds the finger 8 against the brush and forces the brush inwardly against 95 the commutators. By these means contact is maintained between the brush and the commutator, as the brush wears down, while 100 105

the longitudinal opening along the exposed side of the guide tube 1 provides ready access to the brush. The inner end of the brush is guided by two ears or lugs 12 struck out from the respective supporting arms 3 and 4. To provide attaching means for the motor terminal the upper supporting arm 3 is slotted and a portion bent double upon itself to provide a terminal clamping tongue 13. A screw 14 clamps the tongue upon the terminal while the resiliency of the metal serves to release the terminal when the screw is relieved.

It will be observed that the holder forms 15 a unitary structure which is conveniently attached to or removed from the motor, and being composed entirely of sheet metal, it may be easily and cheaply produced.

It is obvious that various modifications 20 may be made in the construction shown in the drawings and above particularly described within the principle and scope of my invention.

I claim:

25 1. In a dynamo-electric machine, a brush holder comprising a guide tube open along one side, a movable pressure member adapted to bear against the rear end of the brush in the guide tube and including a portion 30 extending in front of the longitudinal opening and arranged to prevent the brush from escaping from the opening, and resilient means engaging the pressure member and holding it resiliently against the rear end 35 of the brush.

2. In a dynamo-electric machine, a brush holder comprising a guide tube open along one side, a supporting arm for the guide tube, a pressure arm pivoted to the supporting arm and having a brush-engaging finger extending into the longitudinal opening in rear of the brush and having a handle portion extending in front of the longitudinal opening and arranged to prevent the brush from escaping from the opening, and resilient means tending to rotate the pressure arm upon its pivot to resiliently press the brush-engaging finger against the rear end of the brush.

end of the brush and hold the brush in yielding engagement with a commutator. 50

3. In a dynamo-electric machine, a brush holder comprising a sheet metal guide tube for the brush having a longitudinal opening along one side affording access to the brush in the guide tube, a supporting arm for the guide tube integral therewith, a pressure arm pivoted to the supporting arm and having a brush-engaging finger extending into the longitudinal opening in rear of the brush and having a handle portion extending in front of the longitudinal opening and arranged to prevent the brush from escaping from the opening, and resilient means tending to rotate the pressure arm upon its pivot to resiliently press the brush-engaging finger against the rear end of the brush and hold the brush in yielding engagement with the commutator. 60 65

4. In a dynamo-electric machine, a brush holder comprising a sheet metal guide tube for the brush having a longitudinal opening along one side affording access to the brush in the guide tube, two oppositely extending supporting arms integrally joining the tube at the respective edges of the opening, a pressure arm pivoted to one supporting arm and having a brush-engaging finger extending into the longitudinal opening in rear of the brush and having a handle portion extending in front of the longitudinal opening and arranged to prevent the brush from escaping from the opening, resilient means tending to rotate the pressure arm upon its pivot to resiliently press the brush-engaging finger against the rear end of the brush and hold the brush in yielding engagement with the commutator, a terminal securing finger integral with the other supporting arm and co-operative therewith to clamp an electric terminal, and a clamping screw operative to draw the finger and supporting arm together to exert the clamping action. 70 75 80 85 90 95

In witness whereof I subscribe my signature.

CHARLES H. J. DILG.
